UNITED STATES PATENT OFFICE.

THOMAS HUGH PARKER, OF KEW GARDENS, ENGLAND, ASSIGNEE TO HENRI CLAUDEL, OF LEVALLOIS-PERRET, NEAR PARIS, FRANCE.

CARBURETER.

1,117,233.

Specification of Letters Patent. Patented Nov. 17, 1914.

Application filed August 12, 1913. Serial No. 714,698.

To all whom it may concern:

Be it known that I, THOMAS HUGH PARKER, a subject of the King of Great Britain and Ireland, residing at 44 Mortlake road, Kew Gardens, in the county of Surrey, England, consulting engineer, have invented a certain new and useful Carbureter, of which the following is a specification.

This invention relates to carbureters for use with internal combustion engines and for other purposes and has for its object to provide simple and effective means for controlling the supply of air to the carbureter and the supply of combustible mixture therefrom, while at the same time insuring that the mixture of air and vapor is uniform.

According to the invention a closely wound helical spring closed at each end is provided and the air, on its entry into the carbureter, is caused to pass between and into the coils of the spring. Within the spring the jet for the hydrocarbon is disposed. The combustible mixture of hydrocarbon vapor and air is then passed outwardly between the coils of the spring at the farther end thereof, and is led from the carbureter for use.

The spring is mounted under the action of suitable controlling means to vary the relation of the coils by which it may be extended to increase the area of the space or passages between its respective coils through which the air passes inwardly or the combustible mixture outwardly.

The passage of the air between the coils of the spring serves to break it up or divide it at the moment that it is brought into contact with the hydrocarbon vapor for mixture therewith, and a similar effect of intimate division or admixture is produced upon the combustible mixture as it leaves the spring.

Any convenient number of such springs may be provided in the carbureter and where more than one is used they may be provided with separate or common controlling means as desired.

The application of the invention is illustrated in the accompanying drawings, in which—

Figure 1 is a sectional elevation of a carbureter having a single helical spring. Fig. 2 is a sectional elevation of a carbureter having three helical springs, taken on the line $\alpha-\alpha$ of Fig. 3. Fig. 3 is a plan of

the carbureter represented in Fig. 2, the cover plate being removed.

In carrying the invention into effect as illustrated in Fig. 1, the carbureter casing is constituted by two parts a b adapted to be fitted together and each having an enlarged portion with a laterally disposed passage or aperture a^1 b^1 . The part a is advantageously integral with the float chamber c which is of any convenient construction. At its upper end the part a is screw-threaded on the exterior to engage with an internal screw-thread on the part b . A tube d , within which the spring is slidably carried and having a shoulder or flange at its upper end, is fitted in the part a and secured in position by the screwing home of the part b , which is provided with a suitable shoulder to engage the shoulder or flange of the tube d . A lock-nut is preferably provided to maintain the parts a b in the adjusted relative positions.

The helical spring e is screwed or otherwise secured within a recess at the upper end of a plug a^2 which is seated at the lower end of the part a and secured in position by a cap a^3 screwed upon its projecting extremity. At its upper end the spring is screwed into or otherwise secured to a cap f carried by a rod f^1 or wire which passes through a cap b^2 at the upper end of the part b and is connected to suitable means by which the cap f may be lifted at will for the extension of the spring e to vary the relation of the coils thereof. The said means may consist of a Bowden wire mechanism. The spray nozzle or jet g is mounted within the spring e upon the plug and communicates by suitable passages therein with the float chamber. The air or gas is admitted to the carbureter by the inlet aperture a^1 and passes inwardly between the coils of the spring, the spring being extended as determined, and then mixing with the hydrocarbon vapor from the nozzle passes upwardly along the spring and outwardly between the coils of the spring adjacent the cap f and away from the carbureter by the exit aperture b^1 .

In the construction illustrated in Figs. 2 and 3 a cylindrical carbureter casing h is provided having two transverse partitions h^1 h^2 in which the tubes d for the several springs e are carried, the tubes passing through holes in the upper partition h^1 and

resting with their flanges thereon, and being screwed at their lower ends to fit the holes in the lower partition h^2 . At the lower end of the casing there is a transverse partition h^2 having holes to receive the plugs i to which the lower ends of the springs e are secured and which carry the spray nozzles or jets g . The caps f at the upper ends of the springs e are provided with screwed spindles which pass loosely through a three-armed plate j and are adapted each to receive a nut by which it may be adjusted relatively to the plate j which is carried by a spindle j^2 centrally disposed in the casing h and passing through the lower end for attachment to the controlling means.

The upper end of the casing h is closed by a cover plate k having an outlet aperture k^1 for the explosive mixture, while the lower end is closed by a cover plate l which forms with the partition h^2 a chamber for the hydrocarbon from the float chamber c . Alternatively the partition h^2 may be provided integrally with the cover plate l instead of with the casing h .

The inlet aperture k^2 for the air or gas is disposed at one side of the casing h , while between the partitions h^1 h^2 there is provided an inlet m and an outlet n to the space between the tubes d and the wall of the casing h for hot water by which the temperature of the carbureter may be maintained.

It will be understood that the invention is not limited to the construction hereinbefore described. The springs may be disposed either horizontally or vertically and they may be closed at the ends in any convenient manner, as by coiling them conically, or by fitting metal plugs or caps upon the open ends. Where a number of springs are provided they may be controlled substantially in the manner hereinbefore described or they may be provided so that they are brought into use one after the other by the same controlling gear or they may be provided with separate controlling gears which may be operated in any suitable manner. Any suitable spray nozzle or jet may be employed but it is preferred to use the jet described in the British patent specifications Nos. 17286 of 1909 and 19076 of 1909 or in the patent specification No. 7212 of 1908. The manner of connecting the nozzle or jet to the float chamber may be varied as is desirable. In any construction of the device the springs may each be replaced by two springs of shorter length attached to the respective ends of a length of tube of the same diameter disposed between them. With such a construction no extension of the spring device occurs within the tube in which it is disposed.

The construction shown in Fig. 1 may be modified in various ways. For example, the

tube d may be screwed on the exterior to receive the two parts of the carbureter casing which are secured in position by one or more lock nuts. Again, the two parts of the casing may be so constructed that the tube d is unnecessary, the spring e being merely disposed within the parts of the casing.

An arrangement according to the present invention may be used for the purpose of mixing gases under pressure. The float chamber is not required but a needle or other valve is used with the jet supplying one of the gases.

The spring device may also be used as a controlling valve or pressure equalizer or reducer, for working either under pressure or a vacuum.

What I claim as my invention and desire to secure by Letters Patent is:—

1. A carbureter, comprising a helical spring closed at its extremities to serve as a carburation chamber and the organ of control for the inlet of air and the outlet of a combustible mixture, means for the separation of the zones for admission of air and for the outlet of the combustible mixture, and means for varying the relation of the coils of the helical spring uncovered for the admission of air and for the outlet of the combustible mixture, and means for the admission of the volatile liquid into the interior of the spring.

2. A carbureter, comprising a helical spring closed at its extremities to form a carburation chamber and for controlling simultaneously the inlet for air into the chamber and the outlet of the combustible mixture therefrom, in combination with a tube partially inclosing the said spring and forming zones for the admission of air and for the outlet of the combustible mixtures, with means for varying the relation of the coils between the extremities of the tube and the extremities of the spring, and means for the admission of volatile liquid to the interior of the spring.

3. A carbureter, comprising a helical spring closed at its extremities to serve as a carburation chamber, in combination with a tube separating the zone for the admission of air into the said chamber and the zone for the outlet of combustible mixture therefrom, with means for varying the separation of the coils of the spring, and the number of the coils comprised within the two zones.

4. A carbureter, comprising a helical spring closed at its extremities forming a carburation chamber, a fixed tube separating the zone for the admission of air from the zone for the outlet of the combustible mixture, and means for moving one of the extremities of the spring.

5. A carbureter, comprising a carburation chamber constituted by two helical springs each closed at their exterior extremities and connected the one to the other by a spring

connecting their interior extremities, with means for feeding the combustible liquid to the interior of the said chamber and means for contracting or extending the said springs.

5 6. A carbureter, comprising a reservoir for the volatile liquid, a casing having an inlet for air and an outlet for the combustible mixture, a plurality of helical springs within the said casing, each forming a carbureting chamber with jets communicating with the reservoir and directing the volatile liquid into the interior of the said

springs, and in combination with each of said springs a tube separating the zones for the inlet of air and the outlet for the combustible mixture, and means for extending or contracting the springs successively. 15

In testimony whereof I have hereunto signed my name to this specification in the presence of two subscribing witnesses.
